UNITED STATES PATENT OFFICE.

ENRICO BERNARDI, OF PADUA, ITALY.

CIRCULATION OF WATER IN CYLINDER-JACKETS.

SPECIFICATION forming part of Letters Patent No. 623,869, dated April 25, 1899.

Application filed October 24, 1898. Serial No. 694,564. (No model.)

To all whom it may concern:

Be it known that I, ENRICO BERNARDI, a subject of the King of Italy, residing at Padua, Italy, have invented certain new and useful 5 Improvements in the Circulation of Water in Cylinder-Jackets; and I do hereby declare the following to be a full, clear, and exact description of the invention, such as will enable others skilled in the art to which it appertains 10 to make and use the same, reference being had to the accompanying drawings, and to letters of reference marked thereon, which form a part of this specification.

This invention relates to an improved device by which the reservoir containing the water which serves for circulating around the cylinders of gas-engines, air-compressors, and the like for the purpose of cooling the same admits of being placed below the cylinder 15 without the necessity of employing a pump for producing such circulation, which in devices of the ordinary kind, where the water is placed above, takes place by reason of the difference of density between the cold water 20 and the heated water.

This improved device is represented in the accompanying drawings, in which—

Figure 1 is a diagrammatic view illustrative of my invention, and Fig. 2 a detail view 30 showing a modification.

A is the working cylinder; *a*, the jacket in which the water is required to circulate; B, the reservoir containing the circulating water, this reservoir being placed below and 35 communicating with the jacket *a* by means of tubes *t* and *s*, terminating, respectively, in the cover and in the bottom of the said reservoir B. The upper end of the tube *t* terminates in a small chest D, open at *f* and communicating with the jacket *a* by means of a 40 conduit U.

v is the exhaust-pipe for the products of combustion. To this exhaust-pipe is connected the pipe *u z x*, which terminates near 45 the cover of a tightly-closed box C. The upper orifice of the pipe *u z x* is provided with an ordinary valve or with a clack-valve adapted to open outward. To the bottom of this box or chest C is connected one end of a 50 small tube *y*, which has its other end inserted

in the tube *s* and is turned down toward the base, the said tube terminating in a nozzle *e* of small diameter.

The water which is introduced into the chest D fills the reservoir B, the tubes *s* and *t*, and the jacket *a*. If under these conditions the products resulting from the combustion taking place in the cylinder escapes direct to the outside, the water contained in jacket *a* and in the chest D will become heated to 55 boiling temperature without heating the water contained in the reservoir B, and consequently no circulation whatever will take place. A portion of the exhaust from the motor, however, passes through the tube *u z x* 60 into the chest C at a pressure higher than that of the atmosphere and lifts the clack-valve, which latter as it redescends upon its seat prevents the exhaust products from flowing back when the driving-piston has 65 reached the end of its exhaust-stroke. The gases contained in the box C then escape through the pipe *y* and the nozzle *e*. A quantity of gas-bubbles mixes with the water contained in the tube *s*, in jacket *a*, and in the 70 conduit U, and causes a stirring effect in the chest D. It is evident that under these circumstances a circulation of water is set up 75 below the horizontal line *e e'*, which said circulation causes a portion of the cold water contained in the reservoir B to rise through the tube *s*, which cold water serves to replace 80 part of the hot water contained in the chest D and jacket *a*, which descends through the tube *t*.

85 The small box or chest C acts as an air-reservoir for producing a uniform flow of the products of combustion at *e*, which products pass in an intermittent manner into the box C. If the pressure in the box C should not 90 be sufficient for effecting the flow of the gases at the nozzle *e*, it will only be necessary to reduce the cross-section of the exhaust-pipe *v* at a suitable point *q*.

95 For applying the device to a compressor instead of to a gas-engine it would only be necessary to omit the tube *u z x* and the chest C and to establish communication between *y* and the air-conduit or gas-pressure conduit. A cock inserted in the communicating con- 100

duit would permit of regulating the flow at the nozzle *e*. This construction is clearly illustrated in Fig. 2 of the drawings, in which *A'* represents the compressor, *y'* the tube leading from the air-conduit to the tank *B*, and *q'* the regulating-cock.

What I claim is—

1. The combination with a motor and a water-jacket for the same, of a reservoir for the water-jacket located below it, a supply-conduit leading from the lower end of said reservoir to the lower part of said jacket, a return-conduit leading from the upper part of said jacket and terminating at the upper end of said reservoir, and a conduit leading from the exhaust of said motor to said supply-conduit, as and for the purpose set forth.

2. The combination with a motor and a water-jacket for the same, of a reservoir for the water-jacket located below it, a supply-conduit leading from the lower end of said reservoir to the lower part of said jacket, a return-conduit leading from the upper part of said jacket and terminating at the upper end of said reservoir, a conduit leading from the exhaust of said motor to said supply-conduit,

and a valve for regulating the pressure therein, as and for the purpose set forth.

3. The combination with the cylinder of a gas-engine and a water-jacket therefor, of a reservoir for said water-jacket located below it, an open chest communicating with the upper part of said water-jacket, a supply-conduit leading from the lower part of said reservoir to the lower part of said jacket, a return-conduit leading from said chest and terminating at the upper part of said reservoir, an exhaust-pipe for the products of combustion from said engine, a closed chest, a pipe leading from said exhaust-pipe to said closed chest and provided with a check-valve, and a pipe leading from said closed chest to said supply-conduit, as and for the purpose set forth.

In testimony that I claim the foregoing as my invention I have signed my name in presence of two subscribing witnesses.

ENRICO BERNARDI.
